UNITED STATES PATENT OFFICE

HERMANN HOFFMEISTER, OF KLEIN-QUENSTEDT, NEAR HALBERSTADT, GERMANY

POTATO GATHERING MACHINE

Application filed August 8, 1929, Serial No. 384,336, and in Germany June 24, 1929.

This invention relates to a machine for gathering potatoes, in which the elevator is raised in a particularly suitable manner from the platform of the machine and can be lowered into any suitable position. For this purpose the elevator is connected by the parts mounted thereon to the rear axle, around which the control of the elevator is effected in that a worm actuates a worm wheel 10 through the turning of a hand crank so that racks are shifted, which are connected to slide blocks, which are mounted on the frame enclosing the elevating device and slide in guides, provided in the stationary carrying frame of the machine so that, according to the control of the slide blocks a gradual raising or lowering of the elevator occurs, through which a very accurate adjustment of the penetration of the conveyer bars into the earth can be effected.

An embodiment of the invention is illustrated by way of example in the accompanying drawings in which

Fig. 1 shows a top plan view and

Fig. 2 a side elevation of the machine.

Fig. 3 shows the upper portion and

Fig. 4 the lower portion of the elevator.

Fig. 5 shows the connection of an elevator bar with the link chains of the elevator.

Fig. 6 is a cross-section through the grid on line 4—4 of Fig. 4.

Fig. 7 shows the specific means for raising and lowering the elevator, disconnected from the rest of the structure.

The machine consists of a frame 1, through which a rear axle 2 is inserted. Front wheels 3 are mounted on vertical rods 4 and adapted to be swiveled in both directions through a steering rod 5. A driver's seat 63 is mounted

on the front end of the frame 1. A top remover 6 is arranged behind the front axle and in operative position extends to within 5 cms. above the surface of the soil. The potato tops are gripped by the trough-shaped, arrow-like top remover and pass along the two inclined side walls of the same to be discharged on both sides of the machine.

The top remover is mounted on a rod 7 and adjustable in a guide 8 by means of a set screw 9.

The elevator for the potatoes consists of two inclined side walls 10 fastened to the rear axle 2 by struts 11. Grid bars 12 standing on edge are arranged between the walls 10. These bars are connected at the upper end by a shaft 13 and held apart by spacing rings 14. Two stays 15 engage on the shaft 13 and are fastened to the struts 11 (Fig. 2). The grid bars are connected at their lower end by a shaft 16 (Fig. 4) and held apart by spacing rings 14. The grid bars 12 terminate each in a point sharpened to a knife edge on the lower end so that the grid can easily penetrate into the soil. The shafts 13 and 16 are journaled in the side walls 10. The shaft 16 is connected by two struts 17 (Fig. 2) to the struts 11 so that with the rising and falling movement of the front part of the gathering device the whole of these struts or stays 11, 15 and 17 carrying this device can oscillate around the rear axle 2.

The elevator is composed of two link chains 18 passing over sprocket wheels 19 keyed on shafts 20. The inner chain links at certain intervals apart constitute rests 21 for rods 22, 75 on which the conveying bars 23 are supported and which form at each end an angular offset portion 24. As shown in Figs. 3 and 4 the conveying bars 23 may in the inoperative position assume any position. As soon however 80 as they come into contact with the grid 12, they are forced by the offset portions into a position approximately perpendicular to the grid, so that they push the dug potatoes in front of them up the grid until they drop at 85 the end thereof onto a jiggling sieve 25 (Fig. 1), vibrated sideways by a crank 26 acting on a rod 27 movably fitted on the jiggling sieve 25. The crank 26 is driven by a pair of bevel wheels 28 and 28' from the upper sprocket 90 wheel shaft 20. The jiggling sieve 25 is connected by means of two links 29 (Fig. 2) with a rod 30 carried by the shaft 13. The jiggling sieve 25 rests on a frame 31 in alignment with and connected to the struts 17. The 95 delivery chute 32 for the potatoes falling from the jiggling sieve extends from the frame 31. Hooks 33 for suspending sacks are fastened on the frame 31. On downwardly extending arms 34a platform 35 is suspended 100

from the frame 31 on which platform the worker stands for attaching and removing the sacks.

The drive of the elevator is effected from the rear axle 2 by means of a sprocket wheel 36 and a chain 37 onto a sprocket wheel 38 keyed on the shaft 20. A clutch element 39 is connected to the sprocket wheel 38, a counter clutch element 41 controlled by a spring 40 being adapted to engage with the clutch element 38. This counter clutch element 41 is capable of being disengaged from the clutch element 39 by a lever 43 oscillatable around a pivot 42. When travelling along a road the lever 43 can be held in disengaged position by a lock pin 44.

For lowering and raising the elevator stop rails 45 are fitted on the outer side of the side walls 10 and rest on dogs or stops 46 fixed on slide blocks 47. The blocks 47 slide in guides 48 (Fig. 2) fixed on the frame 1. On each of the slide blocks 47 a rack 49 is bolted, with which tooth wheels 50 engage. These tooth wheels 50 are mounted on a shaft 60 which is journalled in brackets 60' on the frame 1 and carries on one side of the machine a worm wheel 51, meshing with a worm or endless screw 52 actuated by the rotating of a rod 53 by means of a crank 54 and arranged in lugs 52' projecting from one of the brackets 60'. According to the direction in which the worm wheel 51 is rotated the slide blocks 49 are displaced in their guides 48 in the one or other direction, so that the bars 45 either rise or descend, whereby the desired depth at which the grid bars 12 penetrate into the earth can be adjusted.

Plates 56 mounted on the side walls 10 prevent the link chain 18 being soiled with earth. The arms of these plates may be adjusted by means of set screws.

The link chains 18 are tightened by means of stretching screws 57 (Fig. 2).

I claim:—

In a potato gathering machine, in combination with the machine frame and with the rear axle of the machine, an elevator displaceable in relation to said rear axle, slide blocks, a stop on each slide block, two stop rails on said frame, elevator resting on said stops, an endless screw mounted on said frame, a worm wheel engaging with said endless screw, racks meshing with said worm wheel adapted to raise and lower said elevator around said rear axle, and guides on said machine frame for said blocks.

In testimony whereof I affix my signature.
HERMANN HOFFMEISTER.
